(57) **CLAIM**

The ornamental design for a graphic user interface for a digital camcorder, as shown and described.

DESCRIPTION

FIG. 1 is a perspective view of a graphic user interface for a digital camcorder according to our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is an enlarged view of the graphic user interface for a digital camcorder shown in FIG. 2.

FIG. 9 is an exploded view of a second embodiment thereof;

FIG. 10 is an exploded view of a third embodiment thereof;

FIG. 11 is an exploded view of a fourth embodiment thereof;

FIG. 12 is an exploded view of a fifth embodiment thereof;

FIG. 13 is an exploded view of a sixth embodiment thereof;

FIG. 14 is an exploded view of a seventh embodiment thereof;

FIG. 15 is an exploded view of an eighth embodiment thereof;

FIG. 16 is an exploded view of a ninth embodiment thereof;

FIG. 17 is an exploded view of a tenth embodiment thereof;

FIG. 18 is an exploded view of a eleventh embodiment thereof; and,

FIG. 19 is an exploded view of a twelfth embodiment thereof.

The surface(s) or portion(s) of the article not shown in the drawing or described in the specification form(s) no part of the claimed design. The broken line in the drawing is for illustrative purpose only and forms no part of the claimed design.
